United States Patent [19]**Noodeljik****Patent Number: Plant 11,659****Date of Patent: Nov. 28, 2000**[54] **CHRYSANTHEMUM PLANT NAMED 'OBERON'**[75] Inventor: **Robert Noodeljik**, Woubrugge, Netherlands[73] Assignee: **Chrysanthemum Breeders Association N.V.**, Netherlands[21] Appl. No.: **09/179,457**[22] Filed: **Oct. 27, 1998**[51] **Int. Cl. 7** ..... **A01H 5/00**[52] **U.S. Cl.** ..... **Plt.287; Plt.286**[58] **Field of Search** ..... Plt./286, 287, 297, Plt./298, 292, 293*Primary Examiner*—Howard J. Locker
Attorney, Agent, or Firm—Parkhurst & Wendel, LLP**[57] ABSTRACT**

A chrysanthemum plant named Oberon characterized by its small sized blooms with greyed-red ray florets and prolific branching early natural season flower date of August 4-7; blooming for a period of 6 weeks.

1 Drawing Sheet**1****BACKGROUND OF THE INVENTION**

The new plant of the present invention comprises a new and distinct cultivar of chrysanthemum plant that is a cross of unknown *Dendranthema grandiflora* parents. The new and distinct cultivar was a seedling resulting from the open pollination among groups of chrysanthemum cultivars maintained under the control of the inventor for breeding purposes. The new and distinct cultivar was discovered and selected as one flowering plant by Rob Noodeljik on a 10 cultivated field in Rijenhout, Holland in Aug., 1996. The plant has been asexually reproduced by cuttings in greenhouses at Rijenhout, Holland. The new cultivar has been found to retain its distinctive characteristics through successive propagations. 15

SUMMARY OF THE INVENTION

The present plant is a new and distinct variety of chrysanthemum of a small sized bloom and greyed-red ray 20 florets.

BRIEF DESCRIPTION OF THE DRAWINGS

The present invention of a new and distinct variety of 25 chrysanthemum is shown in the accompanying drawings, the color being as nearly true as possible with color photographs of this type.

FIG. 1 shows the various stages of bloom of the new 30 cultivar.

DESCRIPTION OF THE INVENTION

This new variety of chrysanthemum is of the botanical classification *Dendranthema grandiflora*. The observations 35 and measurements were gathered from plants grown out doors in Rijenhout, Holland under natural day length and temperature and planted week 22 in 1997 and 1998. The natural blooming date of this crop was August 4-7 (week 32). The average height of the plants was 20 cms. This new 40 variety produces small sized blooms with greyed-red ray florets and yellow-green disc florets (only visible at an early stage of inflorescence).

The following is a description of the plant and characteristics that distinguish Oberon as a new and distinct variety. 45

The color designations (color designations are from the R.H.S. Colour Chart) are taken from the plant itself. Accordingly, any discrepancies between the color designa

tions and the colors depicted in the photographs are due to photographic tolerances.

Botanical Classification		
CULTIVAR Oberon		
<u>Bud</u>		
Size	SMALL	CROSS SECTION ±
	1.0 CM	HEIGHT ±1.0 CM
<u>Outside Color Bloom</u>	RED 51 D	
Size	SMALL	
Fully Expanded	4-4½ CM	
Borne (number of blooms per branch)	UPPER AND LOWER PORTION PLURAL	
	BLOOMS PER BRANCH
